UNITED STATES PATENT OFFICE.

FRANK J. ANDERSON, OF GREAT FALLS, MONTANA.

BUTTON-HOOK.

1,255,272.

Specification of Letters Patent.

Patented Feb. 5, 1918.

Application filed October 30, 1916. Serial No. 128,561.

To all whom it may concern:

Be it known that I, FRANK J. ANDERSON, a citizen of the United States, residing at Great Falls, in the county of Cascade and 5 State of Montana, have invented certain new and useful Improvements in Button-Hooks, of which the following is a specification.

This invention relates to button hooks, 10 and more particularly to button hooks of the foldable type.

One of the main objects of the invention is to provide a button hook of simple construction and neat appearance which may 15 be folded so as to be carried in the pocket and, when folded, will present no projections or sharp points which will catch in the clothing. A further object is to provide a button hook in which the hook element 20 will be held rigidly in open position when it is desired to use the hook and, when not in use, will be held securely in closed position within the container or handle. Further objects will appear from the detailed 25 description.

In the drawings:

Figure 1 is a top plan view of the hook in folded position;

Fig. 2 is a side view of the hook in partly 30 open position, the position occupied by the hook when entirely opened being indicated by broken lines; and

Fig. 3 is a section on line 3—3 of Fig. 1.

The handle or gripping element 1 is 35 formed of sheet metal to represent a shoe. At the toe portion of the shoe, this sheet metal is turned downward and inward at right angles to provide two spaced parallel walls 2. These walls have sufficient resili- 40 ence to give laterally toward the sides 3 of the body of the handle. The shaft 4 is formed, adjacent its inner end, at each side, with an integral gudgeon 5. These gudgeons are in alinement transversely of the shank 45 and are adapted to fit into suitable apertures through the resilient walls or supporting plates 2 so as to pivotally secure shank 4 in the handle. This shank is provided, at its outer end, with an integral 50 hook 6.

A spring steel plate 7 made in the form of a shoe sole extends beneath the body of the handle and is secured to the heel portion thereof, as at 8. The distance from 55 the pivotal axis of the shank 4 of the hook to its inner end is such that, when the shank

is turned outward and downward about its pivotal axis, the securing plate 7 will be forced downward. When the shank 4 has been moved into its outermost position the forward end portion of plate 7 engages in recess 4^a in the underface of the shank, near the inner end thereof, and serves to secure the shank in operative position. This recess is of such depth that, when the hook 65 is in operative position, the top of the recess is flush with the bottom of the handle or gripping element and is in tight engagement with the plate 7, the recess 4^a being of such length that the plate has a relatively large bearing surface on the inner end portion of the shank thus firmly securing the same in operative position. When it is desired to move the hook into inoperative position, it is turned upward and inward about its pivotal axis so as to be within the body of the handle 1, in which position the plate 7 is in engagement with the under face of the shank and acts to 70 secure it against movement about its pivotal axis. In this position the open portion of the hook 6 is directed inwardly against the inner face of the sole of handle 1, the hook being in effect an eye which is inclosed within the side walls of the handle. When 75 folded the hook presents a neat appearance and is free of all obstructions such as would tend to catch in the clothing.

The resilient supporting arms 2 may be forced apart by any suitable instrument so 80 as to release the gudgeons 5 thus permitting the removal of the hook. This provides means whereby, in the event of a hook becoming bent or broken, the hook may be quickly and easily removed and replaced 85 by another hook. The arcuate shape of the side portions 3 of the toe section of the handle coöperate with the resilient arms 2 to permit this ready insertion and removal of the hook shank, while normally acting 90 to pivotally secure the same within the handle.

What I claim is:

1. In a button hook, the combination of a handle, and a hook detachably and pivotally secured therein.

2. In a button hook, the combination of a handle, a hook detachably and pivotally mounted therein, and means carried by the handle for securing the hook in adjusted 110 position about its pivotal axis.

3. In a button hook, the combination of

a handle provided with spaced integral arms, a hook pivotally and detachably secured between the arms, and a spring plate carried by the handle and in engagement 5 with the hook for securing the hook in adjusted positions about its pivotal axis, said plate also acting as a closure member for the bottom of the handle.

4. In a button hook, the combination of
10 a handle provided with parallel spaced resilient arms, said arms being provided with aligned apertures, a shank mounted between the resilient arms and provided with laterally disposed gudgeons mounted in said
15 apertures, said shank being further provided with an integral hook, and a spring plate secured on the body and engaging the hook shank beyond its pivotal axis so as to secure the same in adjustment.
- 20 5. In a button hook, the combination of a handle provided with an inclosing wall and having two integral spaced resilient arms provided with aligned apertures, a hook shank mounted between the said arms and provided with laterally extending gudgeons
25

mounted in the apertures, said shank being further provided with an integral hook, and a spring plate secured to the bottom of the handle and in engagement with the hook shank for securing the shank in adjustment 30 about its pivotal axis.

6. In a button hook, a handle of resilient material provided with an arcuate inclosing wall having two integral spaced resilient arms depending therefrom and provided 35 with aligned apertures, a hook-shank mounted between said arms and having laterally extending gudgeons mounted in the apertures, said shank being further provided with a hook, and a spring plate secured to 40 the bottom of the handle and in engagement with the hook-shank for securing the shank in adjustment about its pivotal axis.

In testimony whereof I affix my signature in presence of two witnesses.

FRANK J. ANDERSON.
